DISPENSING DEVICE

Adam Ziska, Wauwatosa, Wis., assignor to Badger
Vending Machines Co., Milwaukee, Wis., a cor-
poration of Wisconsin

Application October 28, 1949; Serial No. 124,069

2 Claims. (Cl. 312—55)

1

This invention relates to improvements in dispensing devices, and more particularly to devices for dispensing individually packaged spoons or the like.

When a food product, such as ice cream, is sold in containers such as paper cups for immediate consumption, it is both desirable and necessary to provide the purchaser with a spoon. Health laws in many States require that such spoons, which are usually formed of wood or cardboard, be protected by a sealed wrapper. In compliance with the law, these spoons are usually packaged in flat paper tubes which are sealed at both ends.

Vending machines as heretofore developed have failed to provide satisfactory means for dispensing wrapped spoons of this type because the thinness of the package combines with the loose fit of the spoon in the paper tube to render the use of conventional spoon dispensing devices unsatisfactory. The reason for this is that jamming often occurs when conventional devices are used.

It is, therefore, a general object of the present invention to provide an improved device for dispensing wrapped spoons or the like.

A further, more specific object of the invention is to provide a device of the class described wherein positive operation and the prevention of jamming is assured by the use of needle elements which are adapted to temporarily impale the package by piercing the spoon through the paper wrapping thereof, said packaged spoon being moved horizontally by said needle elements from the bottom of a stack to a discharge position.

A further object of the invention is to provide a device of the class described which may either be incorporated in a food vending machine, or used separately therefrom.

A further object of the invention is to provide a device of the class described which is relatively simple in construction and inexpensive to manufacture and repair, and which is otherwise well adapted for the purposes described.

In the drawings accompanying and forming a part of this specification, wherein is shown one complete embodiment of the preferred form of the invention, and wherein like characters of reference indicate the same parts in all of the views:

Fig. 1 is a fragmentary front elevational view of the improved dispensing device, part of the front wall thereof being broken away;

Fig. 2 is a vertical sectional view taken approximately along the line 2—2 of Fig. 1;

Fig. 3 is a view similar to Fig. 2 but showing another position of the parts of the improved device during a dispensing operation; and

2

Fig. 4 is a plan view of a packaged spoon of the type the improved device is designed to handle.

Referring more particularly to Figs. 1 and 2 of the drawing, the numeral 10 indicates a generally channel-shaped frame member made of sheet metal and having parallel vertical front and rear walls 11 and 12. The frame 10 also has an upper horizontal wall 13 as well as an angled wall portion 14 joining the front wall 11 with said upper wall 13. Connecting the front wall 11 with the rear wall 12 is a flanged vertical partition 15 which is riveted to said walls as shown.

Positioned on top of the top wall 13 of the frame 10 is a vertically extending elongated storage hopper 16 which is C-shaped in transverse cross-section. The hopper 16 has a pair of spaced front wall flanges 17 and 18, the lower ends of which terminate at a point spaced above the upper wall 13, as at 19 and 20. The hopper 16 is adapted to store a plurality of packaged wooden spoons 21 as shown in Figs. 1, 2 and 3. Referring to Fig. 4, each package 21 comprises a flattened paper tube 22 in which is contained a flat wooden spoon 23 or the like. The ends of the tube 22 are crimped and sealed, as at 24 and 25. Fixed to the lower end portions of the flanges 17 and 18 is a transversely extending member 26 which is generally L-shaped in cross section. The member 26 has a horizontal extent 26, the bottom surface of which is parallel with and spaced above the plane of the upper surface of the wall 13, as shown.

Mounted against the under side of the walls 13 and 14, and extending from the front wall 11 to near the rear wall 12, is a slide supporting and guiding member 27. The member 27 is channel-shaped in transverse cross-section and is formed with a pair of horizontally outwardly directed flanges 28 and 29 at the upper edge of the sidewalls thereof, said flanges being screwed or otherwise attached to the under side of the wall 13, as shown. The member 27 has its front edge cut at an angle to fit the angularity of the wall 14, as shown, and is also formed with a downwardly directed front flange 30 which is screwed or otherwise attached to the front wall 11. The side walls of the member 27 are formed with a pair of elongated matching longitudinal slots 31, and the bottom wall thereof is formed with an elongated longitudinal slot 32.

Slidably mounted in the guiding and supporting member 27 is a slide member 32 which has a rectangular outline in transverse section corresponding to the cross-sectional shape of the area bounded by the inner, bottom and side walls of the member 27 and by the top wall 13 of the

frame 10. The rear wall 12 of the frame 10 is formed with an aperture 33 to permit the slide 32 to project therethrough, and the angled wall 14 is formed with an aperture 34 for the same purpose.

The slide 32 is formed in its under side with a groove 35, which extends from the front end thereof to near the rear end, to give the slide 35 a channel-shaped transverse cross-section for a substantial portion of its length. The slide 32 is formed with a pair of aligned apertures 36 (see Fig. 1) in the opposite sidewalls of the grooved portion thereof. An elongated transverse shaft 37 extends through the apertures 36 and is journaled therein. The shaft 37 slidably projects through the slots 31 in the guide member 27, and at the opposite ends thereof are fixed, as with set screws, arms 38. The arms 38 carry at their outer ends needles 39 which are similar to phonograph needles.

A lever 40, which is formed with an aperture 40' adjacent one end thereof, is positioned with said apertured end in the groove 35 of the slide 32. The lever 40 projects through the slot 34 in the guide member 27 and is also fixedly mounted on the shaft 37, as by a set screw. A pair of stop shoulders 41 and 42 are formed on the lever 40 at the upper end thereof, said shoulders being so positioned as to be engageable with the upper wall of the groove 35 to limit the range of pivotal movement of the lever 40. The lever 40 is bifurcated at its lower end and carries a pin 43 at said end.

An inverted T-shaped lever 44 is pivotally mounted on one side of the partition 15 for movement in a vertical plane parallel with the line of movement of the slide 32. The lever 44 has an upright arm 45 which is slotted at its upper end, as at 46, said slotted end being positioned between the bifurcations of the lever 40 with the shaft 43 received in the slot 46 as shown. The lever 44 has a rearwardly extending arm 47 to which is connected a coil tension spring 48 which is in turn connected to a suitable fixed support (not shown) in a manner to urge the lever 44 in a clockwise direction toward the solid line position of Fig. 2. The lever 44 has a forwardly projecting arm 49, to the end of which is connected a cable 50 or other suitable member by means of which the lever 44 may be urged in a counter-clockwise direction.

The angled wall 14 and the upper wall 13 are formed with a pair of spaced parallel slots 51 each of which extends in the same vertical plane as one of the arms 38, as shown in Fig. 1. Rearwardly of the hopper 16, the upper wall 13 of the frame 10 is formed with an aperture 52 above the slide 32. A friction button 53 is formed on the end of a leaf spring 54 and extends through the aperture 52 into contact with the upper surface of the slide 32, as shown. The leaf spring 54 is fixed to the wall 13 as by a screw 55, said spring being operable to urge the button 53 into frictional engagement with the slide 32.

In operation, the spring 48 normally holds the levers 44 and 40, arms 38, and slide 32 in their solid line inoperative positions of Fig. 2. To dispense a single spoon, the cable 50 is pulled downwardly by any suitable means to cause counter-clockwise rotation of the lever 44 (as viewed in Figs. 2 and 3) against the tension of the spring 48. The first result of this counter-clockwise movement of the lever 44 is to swing the lower end of the lever 40 forwardly until the stop shoulder 41 of said lever abuts the upper wall of the

65

70

75

groove 35 of the slide 32. The position of the parts when said abutment occurs is shown in dot and dash lines in Fig. 2. The shaft 37 is bearinged freely in the apertures 36 of the slide 32 and is slidably movable in the slots 31 of the guide 27. Since the button 53 frictionally engages the slide 32, the lever 40 swings freely, as described, without causing movement of the slide 32 as long as the stop shoulders thereof are not in abutment with said slide.

As the lever 40 swings to the dot and dash line position of Fig. 2, the shaft 37 and the arms 38 fixed thereto are rotated an equal amount to their dot and dash line position shown in said figure. As the arms 38 swing upwardly during said rotation, the needles 39 project through the slots 51, and the points thereof project into the lowermost spoon 21 in the hopper 16. The needles 39 continue to swing upwardly and then lift the entire stack of spoons 21 in the hopper 16 until the upper surface of the lowermost package 21 extends in substantially the same horizontal plane as the lower surface of the horizontal extent 56 of the L-shaped member 26. This condition obtains when the parts are disposed in their dot and dash line positions of Fig. 2.

As the lever 44 is moved further in a counter-clockwise direction toward the position thereof shown in Fig. 3, the forward movement of the upper end of the arm 45 is transmitted to the slide 32, since the lever 40 cannot swing further forward after the shoulder 41 abuts the slide 32. The slide 32, shaft 37 and arms 38 move forwardly toward the positions thereof shown in Fig. 3. As this movement occurs, the arms 38 project through the slots 34 as the lowermost package 21, which is impaled upon the needles 39, is moved forwardly out from under the stack to the position of Fig. 3. More than one package 21 is prevented from leaving the stack by the member 26. As the lowermost package 21 is moved clear of the stack, said stack drops down and is supported on the top of the wall 13, as shown in Fig. 3.

Upon releasing the cable 50, the spring 48 pulls the lever 44 in a clockwise direction. This moves the lower end of the lever 40 rearwardly and rotates the shaft and the arms 39 in a counterclockwise direction until the stop shoulder 42 of the lever 40 engages the upper wall of the groove 35 in the slide 32. Counterclockwise rotation of the arms 38 moves the needles 39 downwardly and retracts said arms and said needles through the slots 34. This swings the impaled package 21 downwardly against the angled wall 14 and withdraws the needle points therefrom. The package then slides down off of the wall 14 into any suitable chute or receptacle (not shown).

Upon abutment of the stop shoulder 42 with the slide 32, continued clockwise rotation of the lever 44 causes rearward movement of the lever 40, shaft 37, arms 38, and the slide 32 to their solid line positions of Fig. 2, and the dispensing cycle is completed.

It is apparent that the improved dispensing device is positive in operation and that there is no possibility of the packages therein being jammed or being otherwise caused to interfere with the operation of the device.

Various changes and modifications may be made without departing from the spirit of the invention, and all of such changes are contemplated as may come within the scope of the claims.

What I claim is:

1. In a dispensing device: a hopper in which packages are adapted to be vertically stacked, said hopper having a front opening at the bottom thereof; a stack support in the bottom of said hopper and having an inclined discharge portion projecting forwardly and downwardly from said front opening, said support being formed with a slot extending from a point within the hopper forwardly into said discharge portion; a slidable member mounted for forward and rearward lateral movement below said hopper; a pointed element vertically movably mounted on said slidable member and normally positioned below said stack support, said element being positioned for movement upwardly through said support aperture into impaling engagement with the lowermost package in said stack; actuating mechanism connected to said pointed element; means responsive to actuation of said pointed element in one direction for sequentially raising the latter to said impaling position and moving said raised element and said slidable member forwardly to move the impaled package completely through the discharge opening and over said projecting support portion; and means responsive to actuation of said pointed element in a reverse direction to cause withdrawal of said element through said support slot in the inclined discharge portion of said support to thereby deposit said package on said inclined discharge portion.

2. In a dispenser for wrapped wooden spoons or the like having a hopper in which said spoons are adapted to be vertically stacked, said hopper having a front opening adjacent the lower end thereof; a stack support at the bottom of said hopper, said support having a downwardly inclined discharge portion projecting forwardly of said hopper front opening and said support being formed with an elongated aperture extending

from a point within the hopper forwardly into said projecting portion; a slidably mounted member positioned for lateral movement forwardly and rearwardly below said stack support; an arm pivotally mounted on said slidable member; a pointed element carried by said arm, said element and arm being normally in retracted position below said support and said hopper, and said pivotal arm being positioned to swing the pointed element upwardly through said support aperture and into impaling engagement with the lowermost spoon in the hopper upon being pivoted in a forward direction; means for causing forward movement of said slidable member upon continued forward actuation of said pivotal arm after impalement of the spoon to cause movement of the raised pointed element forwardly within said support aperture and movement of said spoon completely through the hopper opening and over the projecting support portion, said pivotal arm, upon actuation in a rearwardly direction at this forward position, being swingable downwardly to withdraw the pointed element through the support aperture and thereby strip the impaled spoon therefrom; and means for causing rearward movement of said slidable member and arm upon continued rearward actuation of said arm.
